Application February 17, 1937, Serial No. 126,131
 In Germany March 5, 1936

17 Claims. (Cl. 179—18)

The present invention relates to a circuit arrangement for automatic telephone systems in which call registering takes place on the initiation of a call.

It aims at enabling call registering to be effected over relatively long lines or over lines which on account of their poor condition do not permit of direct current working, while also enabling a call to be released from the calling station from the moment of its initiation.

By call registering in this application is meant the registration or locking in of a call in an automatic switch.

In contradistinction to arrangements in which call registering is initiated by operating a magneto and is only released when the call has been switched through to succeeding devices or after an operator has entered the call, in the present arrangement the initiation of the registering is similarly effected by direct current but the registering can be suppressed by the calling station at any time as soon as the call has been initiated.

This is achieved in that a call receiving relay 25 operated by an induced impulse in a particular direction, when the calling subscriber carries out the necessary switching measure for initiating a call, is deenergized by an induced impulse in the opposite direction when the calling subscriber abandons the setting up of the call.

The arrangement according to the invention enables an efficient system to be produced by using switching elements of normal construction which fulfill the conditions imposed by a modern system.

The device for generating induced impulses enables the induced impulses following the operation of the dial switch to be transmitted without the transmission of induced impulses in opposite directions when initiating and abandoning a call being disturbed.

In the drawing an embodiment of the invention is represented to which embodiment the invention is, however, not limited. T_n represents 45 a subscriber's station at which a call may be initiated by removing the telephone receiver. H_u represents the contacts operated by the switch-hook, these contacts being switched over when the receiver is removed. H represents a device 50 which is provided at the station for producing an induced impulse. A considerable range of impulses can be produced so that it can be used even when the connecting lines are in bad condition.

55 When the subscriber at station T_n takes up his

receiver the switch-hook contacts H_{u1} and H_{u2} are switched over. By the switching over of contact H_{u1} the speech repeater G and the telephone receiver F are connected to the line while the bell S is disconnected. The switching over of contact H_{u2} establishes the following circuit: negative pole of battery B , switch-hook contact H_{u2} , contact nsa which is switched over only when the dial plate is operated, relay K , contact $2s$ and positive pole of battery B . Relay K energizes and operates contacts $3k$, $4k$, and $5k$. Winding of the transformer Tr is connected to the battery B by contact $4k$. An induced impulse produced in winding II by the completion of this circuit is, however, not transmitted over the connecting line La since contact $5k$ closes later than contact $4k$. The switching over of contact $3k$ operates relay S . This energizes in the following circuit: positive pole of battery B , relay S , contact $3k$, switch-hook contact H_{u2} , negative pole 20 of battery B . Contact $1s$ opens the circuit over winding I of the transformer generating an impulse which passes over winding II of the transformer Tr , contact $5k$, lead La , winding I of call relay R and contact $8t$ to earth at $E2$. Relay R 25 is caused to energize by this impulse and switches over its contacts $6r$ and $7r$. The following locking circuit is established for winding II of relay R : earth, battery, winding II of relay R , contacts $6r$ and $9t$, starting relay An and earth. Contact 30 $7r$ characterizes the calling line on wiper sc of the call finder AS . Relay An causes the free call finder to be started up in known manner.

After relay S has energized in the device H relay K is caused to deenergize through the switching over of contact $1s$ since it is short-circuited by the following circuit: contact $1s$, relay K , contact nsa , switch-hook contact H_{u2} , contact $1s$. Relay K on releasing restores contacts $3k$, $4k$, and $5k$ to normal. Relay S is held energized in the 40 following circuit: positive pole of battery B , relay S , resistance Wi , contact $1s$, negative pole of battery B .

If now the calling subscriber abandons the call before the call finder AS is switched through, 45 then when the receiver is replaced an induced impulse is transmitted in the opposite sense to the induced impulse previously transmitted by the device H in that when the switch-hook contacts are restored to normal the following circuit is 50 thereby established: positive pole of battery B , contact $2s$ switch-hook contact H_{u2} , contact nsa , relay K , contact $1s$, negative pole of battery B . In this circuit relay K energizes. Contact $5k$ connects winding II of the transformer Tr to the 55

lead La . Contact $3k$ short-circuits relay S in the following circuit: positive pole of battery B , relay S , contact $3k$, switch-hook contact $Hu2$, contact $2s$, positive pole of battery B . Relay S releases. The energizing circuit provided for winding I of transformer Tr is closed at contact $1s$. This energizing of winding I of transformer Tr effects the transmission of an induced impulse to winding I of relay R . Since this impulse is produced by the closing of the circuit for winding I of transformer Tr it is in the opposite direction to the impulse which was transmitted when the call was initiated by the opening of the circuit for winding I of transformer Tr . Relay R is accordingly deenergized by being de-magnetized. Contact $6r$ is opened so that the registering circuit passing over winding II of relay R is disconnected. The arrangement shown is now in the normal condition.

It should be mentioned that subscriber Tn can also be connected to the exchange device over two leads. In this case the connection to earth at points $E1$ and $E2$ must be disconnected and these points connected by a line.

The device H for producing induced impulses is also adapted for transmitting numerical impulses. When the call has been initiated the testing relay P associated with the call finder energizes in the known way. Relay T thereupon also energizes and opens contacts $8t$ and $9t$. Contact $10t$ is closed and maintains the testing circuit. An impulse receiving device is connected up in any desired manner (not shown) and is influenced over wipers sa and sb of the call finder. The calling subscriber receives a signal from the public exchange.

As already described when the call was initiated winding I of relay R was energized by an impulse produced by breaking the circuit for the transformer Tr . Relay S was energized. When now the subscriber at station Tn operates his dial switch contact nsa is closed. Relay K is energized over the positive pole of battery B , contacts $2s$ and nsa , relay K , contact $1s$ and the negative pole of battery B . Relay K operates its contacts. No impulse is transmitted since relay S is energized and accordingly contact $1s$ is operated. As the dial plate runs back contact nsa remains closed while contact nsi is intermittently operated. On account of the closing of contact nsi the following circuit is established for winding I of transformer Tr : positive pole of battery B , winding I of transformer Tr , contact nsi , switch-hook contact $Hu2$, negative pole of battery B . An induced impulse is accordingly transmitted and is followed on the opening of contact nsi by an induced impulse in the opposite direction. The latter induced impulse transmitted on dialling is accordingly an impulse which is produced by breaking the circuit for the transformer Tr so that if the call is abandoned by replacing the receiver at the station Tn another "closing impulse" is produced in the manner already described. This impulse can be used for releasing the call in any known manner. After the transmission of this "closing impulse" by the deenergizing of relay S relay K also releases. Since contact $5k$ opens before contact $4k$ no impulse is transmitted when relay K releases.

What is claimed is:

1. In a telephone system, a line, a telephone substation thereon, means for extending connections from said line, means at the substation for setting up a calling condition in the first

means by transmitting a single impulse of one polarity responsive to the removal of the receiver from the hook switch at the substation, and means for transmitting a single impulse of another polarity to remove the calling condition responsive to the replacement of the receiver.

2. In a telephone system, a line having a substation thereon, a local circuit at the substation inductively associated with said line, call extending devices for extending calls from the line, means responsive to an operation at a calling substation for originating an impulse in said local circuit to cause a single induced impulse to be transmitted over the line to said extending devices to initiate the extension of a call from the line, and means responsive to another operation at the calling substation for originating an impulse in said local circuit to cause a single induced impulse to be transmitted over the line to said extending devices to terminate a call.

3. A telephone system as claimed in claim 2 in which the two induced impulses are in opposite directions.

4. In a telephone system, a line, a circuit associated therewith, a relay connected to the line and controlled thereover to extend connections therefrom, means for transmitting over said line an impulse induced therein from said circuit to operate said relay to initiate the extension of a connection, means for disconnecting said relay from the line responsive to the extension of said connection, and means for transmitting over said line a second impulse induced therein from said circuit to the relay to deenergize it before the extension has been made.

5. In a telephone system, a line, a circuit inductively associated therewith, means for extending connections from said line, means for controlling said circuit to cause a single induced impulse to be transmitted over the line to initiate a call and a single impulse induced in the opposite direction to be transmitted to release an initiated call, and means responsive to the operation of the calling device on said line for transmitting induced impulses over the line to further extend the connection after initiation and before release.

6. In a telephone system, a line, a circuit associated therewith, an automatic switch, a line relay for the line, means for transmitting over said line an impulse induced therein from said circuit to energize said relay to initiate the operation of said switch, means for maintaining said relay energized responsive to said energization of same by the induced impulse, means for transmitting another induced impulse to the relay to deenergize it before the connection is extended, and means for transmitting other induced impulses to complete the extension of a connection from the line if the relay is not deenergized before the connection is extended.

7. In a signalling system, a signalling station and a line circuit therefor, a local circuit at said station, a source of direct current for said local circuit, means at said station for controlling said source to cause the amount of current flowing in said local circuit to increase and to decrease, and means for inductively associating said local circuit with said line circuit only while the flow of current in said local circuit is constant or increasing, thereby to induce signalling current in but one direction in the line circuit.

8. In a signalling system, a signalling station

- and a line circuit therefor, a local circuit at said station, a source of direct current for said local circuit, means at said station for controlling said source to cause the amount of current flowing in said local circuit to increase and to decrease, and means for inductively associating said local circuit with said line circuit only while the flow of current in said local circuit is constant or decreasing, thereby to induce signalling current in but one direction in the line circuit.
9. In a signalling system, a signalling station and a line circuit therefor, a local circuit at said station, means for causing impulses of direct current to flow in said local circuit, and means for inductively associating said local circuit with said line circuit, said last means at times effective only while the current in the local circuit is constant or increasing, at other times effective only while the current in the local circuit is constant or decreasing, and at still other times effective while the current in said local circuit is constant, increasing or decreasing, whereby signalling current induced in the line circuit is at said times in one direction, at said other times in the opposite direction, and at said still other times in both directions.
10. In a telephone system, a subscriber's station and a line therefor, a local circuit at said substation, means at said substation operable either to initiate or to terminate a call, means for causing an impulse of direct current to flow over said circuit responsive to an operation of said last means either to initiate or to terminate a call, and means for inductively associating said circuit with the line, either only during the growth of current in said circuit upon the initiation of said impulse or only during the decay of current in said circuit upon the termination of said impulse in dependence upon whether said impulse is responsive to the initiation of a call or to the termination of a call, whereby current is induced in the line in a distinctive direction in dependence upon whether said first means is operated to initiate or to terminate a call.
- 45 11. In a signalling system, a signalling station and a line therefor, an electromagnetic responding device to be controlled over said line, a local circuit at the station, means for causing an impulse of direct current to flow in said circuit, and means for inductively associating said circuit with the line, said last means at times rendered ineffective during the growth of current in said circuit upon the initiation of said impulse and rendered effective during the decay of current in said circuit upon the termination of said impulse thereby to transmit current induced in one direction over the line to operate said device in one way, said last means at times rendered effective during the growth of current in said circuit upon initiation of said impulse and ineffective during the decay of current in said circuit upon the termination of said impulse thereby to transmit current induced in another direction over the line to operate said device in a different way.
- 65 12. In a system such as claimed in claim 11, means for extending connections from said line, wherein said device is effective to initiate the extension of a connection from said line by said last means or to terminate the extension of a connection from said line by said last means in dependence upon which of said ways said device is operated.

13. In combination, a transformer, a source of direct current for the primary winding of said transformer, means for controlling said source to cause the amount of current flowing through said primary winding to increase and to decrease, and means controlled by said last means for rendering the secondary winding of the transformer effective while the current in the primary winding is increasing and ineffective while the current in the primary winding is decreasing, whereby current is induced in but one direction in said secondary winding.
14. In combination, a transformer, a source of direct current for the primary winding of said transformer, means for controlling said source to cause the amount of current flowing through said primary winding to increase and to decrease, and means controlled by said last means for rendering the secondary winding of the transformer ineffective while the current in the primary winding is increasing and effective while the current in the primary winding is decreasing, whereby current is induced in but one direction in said secondary winding.
15. In a signalling system, a signalling station and a line therefor, a transformer at said station having a secondary winding associated with said line, a source of current for the primary winding of the transformer, and means at said station for controlling said source to cause the amount of current flowing through said primary winding to increase and to decrease, said secondary winding connected to said line while the current in the primary winding is increasing and disconnected therefrom while the current in the primary winding is decreasing, whereby induced signalling current is transmitted over the line in but one direction.
- 20 16. In a signalling system, a signalling station and a line therefor, a transformer at said station having a secondary winding associated with said line, a source of current for the primary winding of the transformer, and means at said station for controlling said source to cause the amount of current flowing through said primary winding to increase and to decrease, said secondary winding disconnected from said line while the current in the primary winding is increasing and connected thereto while the current in the primary winding is decreasing, whereby induced signalling current is transmitted over the line in but one direction.
- 25 17. In a signalling system, a signalling station and a line therefor, a transformer at said station having a secondary winding associated with said line, means for at times causing an impulse of direct current to flow through the primary winding of the transformer thereby to cause induced signalling current to flow in one direction through the secondary winding of the transformer and over said line, and means for at other times causing an impulse of direct current to flow through the primary winding in the same direction as said first mentioned impulse of direct current thereby to cause induced signalling current to flow through the secondary winding of the transformer and over said line in a direction different from that in which said first induced current flowed.
